UNITED STATES PATENT OFFICE

CAMILLE DREYFUS, OF NEW YORK, N. Y.

ELASTIC FABRIC

No Drawing.

Application filed August 8, 1930. Serial No. 474,068.

This invention relates to elastic fabric and relates more particularly to the preparation of an elastic fabric that is not as readily soiled as the prior material and which can be cleaned 5 readily.

An object of my invention is to prepare elastic fabric that does not readily soil and which is easily cleansed. Another object of my invention is to prepare elastic fabric containing rubber or other resilient thread and 10 yarns of cellulose acetate or other organic derivatives of cellulose.

Elastic fabrics are used widely for making articles such as garters, corsets and the like. 15 Such elastic fabrics contain rubber threads for imparting resiliency and also yarns of fibres such as cotton, natural silk or reconstituted cellulose. Such articles are generally worn close to the human body and therefore 20 tend to soil readily. Cotton, natural silk, wool or reconstituted cellulose fibres that have heretofore been employed are quite pervious to dirt, grease, moisture, perspiration and the like and therefore become soiled very 25 readily. Moreover this soiling is so deep-seated that in order to clean the elastic fabric, such drastic scouring must be resorted to that the rubber is deteriorated to such an extent that the utility of the fabric is impaired or 30 even destroyed.

I have found that if elastic fabric is made by employing yarns containing filaments of cellulose acetate or other organic derivatives of cellulose instead of the yarns of the other 35 textile fibres heretofore employed, the resulting fabric is superior to those heretofore made. The cellulose acetate yarn is relatively impervious to dirt, grease, moisture, perspiration and the like and therefore the 40 elastic fabric containing it does not soil readily. Moreover when such fabric does soil, a very light washing in water of relatively low temperature containing a mild soap is sufficient to clean the same, and such 45 light washing does not appreciably impair

the properties of the rubber threads. A further advantage accruing from the use of the cellulose acetate yarn in accordance with this invention is that perspiration does not tend to weaken the same as in the case of 50 other textile fibres.

In accordance with my invention the elastic fabric may be made by weaving or knitting yarns containing filaments of cellulose acetate or other organic derivatives of cellulose with threads of rubber or other elastic or resilient material in any known or suitable manner. While this invention is described specifically in connection with yarns containing cellulose acetate, yarns containing other organic derivatives of cellulose such as organic esters of cellulose and cellulose ethers may be employed. Examples of organic esters of cellulose other than cellulose acetate are cellulose formate, cellulose 55 propionate and cellulose butyrate, while examples of cellulose ethers are ethyl cellulose, methyl cellulose and benzyl cellulose.

Elastic fabric made in accordance with this invention may be used for making wearing apparel consisting in whole or in part of such elastic fabric. By way of example, garters (both hose and sleeve), belts, corsets, girdles, brassieres, trouser braces, elastic bands for bloomers, trousers and the like 70 may be made with my elastic fabric. Another use for elastic fabric is in the making of athletic or surgical bandages or articles such as ankle braces, stockings, sleeves, abdominal braces and the like. 75

It is to be understood that the foregoing description is given merely by way of illustration, and that many variations may be made therein without departing from the spirit of my invention.

Having described my invention, what I desire to secure by Letters Patent is:

1. An elastic fabric containing yarns of an organic derivative of cellulose and rubber threads.

2. An elastic fabric containing yarns of cellulose acetate and rubber threads.
3. Wearing apparel comprising an elastic fabric containing yarns of organic derivatives of cellulose and rubber threads.
4. Wearing apparel comprising an elastic fabric containing yarns of cellulose acetate and rubber threads.

In testimony whereof, I have hereunto
10 subscribed my name.

CAMILLE DREYFUS.
